COMBINED FORK AND SPOON

Anthony M. Dedic, Sr., 4142 Sweet Gum Drive,
St. Louis, Mo.

Filed Feb. 17, 1964, Ser. No. 78,654

Term of patent 14 years

(Cl. D44—29)

FIG. 1.

FIG. 2.

FIG. 3.

FIG. 4.

FIGURE 1 is a perspective view of a combined fork and spoon, showing my new design;

FIGURE 2 is a top plan view thereof;

FIGURE 3 is a side elevational view thereof; and

FIGURE 4 is a front view.

The design of the combined fork and spoon is characterized by a bowl in combination with tines, the root ends of which are in substantially parallel alignment with the tips of four upwardly-projecting tines, the outer tip of the fifth tine being displaced inwardly toward the bowl, the roots and tips of the four tines being disposed on parallel lines forming obtuse angles relative to the longitudinal axis of the bowl, the tines being asymmetrically arranged with respect to the longitudinal axis of the bowl, and the bowl having longitudinally-extending opposed side edges terminating in a common plane.

I claim:

The ornamental design for a combined fork and spoon, as shown and described.
